(57) **CLAIM**

The ornamental design for “digital video disk player,” as shown and described.

DESCRIPTION

FIG. 1 is a right top front perspective view of the digital video disk player in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a perspective view similar to FIG. 1 but showing a disk-loading tray in an open position.

1 Claim, 7 Drawing Sheets
